Primary Examiner — Mojtaba Tehrani(74) *Attorney, Agent, or Firm* — Lee & Hayes, P.C.**CLAIM**

The ornamental design for a pellet, as shown and described.

DESCRIPTION

FIG. 1 is a front perspective view of a pellet; FIG. 2 is a cross-sectional view thereof taken along line 2-2 shown in FIG. 1; FIG. 3 is a top, front perspective view thereof; and, FIG. 4 is a bottom, front perspective view thereof. The dashed lines depict portions of the pellet that form no part of the claimed design. The dot-dashed broken lines represent boundaries of the claimed pellet and form no part of the claimed design.
